UNITED STATES PATENT OFFICE

2,253,373

SELF-CLEANING SANITARY COMB

Louis Greenspan, Brooklyn, N. Y.

Application March 1, 1939, Serial No. 259,808

2 Claims. (Cl. 132—28)

This invention relates generally to a self-cleaning sanitary comb of the type described in my U. S. Patent No. 2,072,673 dated March 2, 1937, but more specifically to a self-cleaning comb provided with an auxiliary strip mounted between the ends of the main comb body and below the top edge thereof.

The main object of the invention resides in the provision of a comb having the usual comb body and front tooth portion, the body being provided with a longitudinal slot on one side below the top edge for mounting therein and between the ends of said slot a movable strip whose teeth engage the spaces between the upper end of the teeth of the comb body.

A further object of the invention resides in the provision of a comb of the above nature wherein a strip containing teeth is pivotally mounted within the ends of a longitudinal slot of a comb body below the upper edge thereof, the teeth of the said strip engaging the spaces between the upper end of the teeth of the comb body.

Another object of the invention is to provide a self-cleaning comb wherein a longitudinal movable strip having teeth is mounted within a longitudinal slot situated on the comb body below the upper edge thereof and springably secured thereto whereby the strip is pivotally movable and limitedly displaceable relative to the comb body.

These objects and other incidental ends and advantages of the invention will hereinafter appear in the progress of the disclosure and as pointed out in the appended claims.

Accompanying this specification are drawings showing preferred forms of the invention wherein corresponding reference characters designate corresponding parts through the several views and wherein:

Figure 1 is a view in perspective showing an embodiment of a self-cleaning sanitary comb in assembled and operating condition.

Figure 2 is a vertical sectional view taken through an end slot of the comb shown in Figure 1.

Figure 3 is a foreshortened view in elevation of a strip adapted to engage the main body of the self-cleaning comb.

Figure 4 is a fragmentary view in elevation of one side of the main comb body showing a longitudinal slot below the upper edge thereof and above the tooth portion, the said slot being adapted to engage the strip shown in Figure 3.

Figure 5 is a fragmentary view in elevation of another form of a main comb body having a

longitudinal slot below the upper edge thereof, the ends of the slot having outwardly inclined walls.

Figure 6 is a foreshortened top plan view of a modified self-cleaning comb utilizing the main comb body shown in Figure 5.

Figure 7 is a fragmentary view in perspective of a strip portion adapted to engage the slot of the main comb body shown in Figure 5.

Figure 8 is a fragmentary view in elevation of one side of another form of comb body showing a longitudinal slot below the upper edge thereof and one of a plurality of recesses along the wall of the slot.

Figure 9 shows the comb body of Figure 8 engaged by a strip within its slot, the said strip being springably secured to the main comb body.

In accordance with the invention and in accordance with the preferred forms shown in the drawings, numeral 10 indicates a conventional comb body having a set of conventional combing teeth 11 depending therefrom. Below the upper edge of comb body 10 and on one side is provided a longitudinal slot 12 being reduced in width near each end, the reduced portions extending to the ends of the comb body as indicated by numeral 13. Within each of the shoulders thus formed at the ends of slot 12, is provided a horizontal opening 14 into each of which is journaled a pin secured to each end of a longitudinal strip adapted to be engaged within the slot 12.

The strip above mentioned is indicated by numeral 15, the width of which is reduced near each of the ends thereof as indicated by numeral 16. A pair of lugs 17 are adapted to be secured to the ends of strip 15 and to project out from the ends of comb body 10 for purposes hereinafter to be described. Below strip 15 are a plurality of teeth each designated by numeral 19, the said teeth having offset front faces and being adapted to engage the spaces between teeth 11 at their upper ends when strip 15 is engaged by slot 12 by means of the insertion of pins 18 into orifices 14. For strip 15 to be pivotally movable about comb body 10, end lugs 17, projecting beyond the ends of comb 10, are grasped by the fingers and slight inward pressure is applied whereby teeth 19 may be rotated forwardly. In this manner, the sediment, dirt and other improper deposits which have accumulated on teeth 19 are removable. When teeth 19 of strip 15 have been rotated out of engagement with teeth 11 in the above manner, it is very simple to remove strip 15 by bearing a little more pressure inwardly of lugs

17 to flex the strip 15 whereby pins 18 are freed of orifices 14. This flexing operation is also necessary in assembling strip 15 with comb body 10.

Figures 5, 6 and 7 show a modified form of self-cleaning comb wherein 20 represents a comb body, 21 the tooth portion thereof, and 22 represents a longitudinal slot below the upper edge and on one side of the comb body, the said slot being reduced in width at the ends as indicated by numeral 23. The end walls of slot 22 above the reduced portions are each inclined towards the ends of the comb body as at 24. Adapted to engage with walls 24 are walls 26 of matched inclination, the said walls 26 being formed in a strip 25 having reduced ends 27. Strip 25 is provided with a set of teeth 28, while the reduced ends 27 of strip 25 are adapted to extend through end slot portions 23 beyond the ends of comb 20. In order to fit strip 25 into the comb body 20, it is necessary to flex the said strip between the ends 27 whereby the inclined walls 24 and 26 are made to engage each other. Upon release of pressure engagement is made secure. In order to remove strip 25, it is necessary to flex the same by inward pressure on ends 27 thereby bodily removing the strip 25 from comb body 20 for purposes of cleaning.

Figures 8 and 9 show a still further modification of a self-cleaning comb wherein 29 represents the comb body, 30 the comb teeth associated therewith and 31 a longitudinal slot disposed on a side of the body 29 below the upper edge thereof. Slot 31 near the ends of comb body 29 are reduced as at 32. Along the surface of slot 31 are a series of cylindrical recesses 33 each having a central opening 34. A strip 35 is provided having reduced end portions 36 to engage the slot 31 and its reduced ends 32. It is to be observed that the ends 36 of strip 35 may project as shown beyond the slot ends 32. A series of registering recesses 37 are provided along an opposing surface of strip 35 as shown in Figure 9 whereby housings are formed, each of the recesses 37 being provided with central orifices 38. Within the said housings are provided helical springs 39 whose terminals may be anchored at openings 34 and 38 of each housing as shown in Figure 9. The strip 35 is pro-

vided with the usual set of teeth similar to teeth 19 or 28.

In order to remove strip 35 for purpose of cleaning the teeth thereon, projecting ends 36 of strip 35 may be rotated forwardly. Upon the releasing of pressure on the ends 36, the tension of springs 39 will bring back the strip 35 into place. It is thus seen that in the modification shown in Figures 8 and 9, strip 35 may either be rotated or pulled forwardly against the tension of the springs 39. Thus has been described a self-cleaning sanitary comb which is pivotal and limitedly displaceable from below the top edge of the main comb body.

I wish it understood that minor changes and variations in the material, position, means of integration, combination and construction of parts, may all be resorted to without departing from the spirit of the invention and without departing from the scope of the appended claims.

I claim:

1. A self-cleaning sanitary comb comprising a comb body having a back and a front tooth portion, the back portion on one side being provided with a continuous longitudinal slot below the top edge, the said slot being reduced at the ends thereof to form opposing shoulders, a strip fitting into the longitudinal slot carrying means to pivotally engage said shoulders, the said strip having short teeth along the lower edge engageable between the upper ends of the teeth of the comb portion.

2. A self-cleaning sanitary comb comprising a comb body having a back and a front tooth portion, the back portion on one side being provided with a continuous longitudinal slot below the top edge, the said slot having reduced end portions to form opposing shoulders, a strip fitting into the longitudinal slot and having short teeth along the lower edge engageable between the upper ends of the teeth of the comb portion, the said strip carrying means inwardly of the ends thereof engageable with said opposing shoulders for pivotal connection between said strip and the comb body, end members secured to the said strip and projecting from the ends of the longitudinal slot to serve as grasping members for movement thereof about the comb body.

LOUIS GREENSPAN.
